UNITED STATES PATENT OFFICE.

GEORGE P. CARROLL, OF BRIDGEPORT, CONNECTICUT.

REFRIGERATING-MACHINE.

1,219,534.

Specification of Letters Patent.

Patented Mar. 20, 1917.

Application filed December 3, 1910, Serial No. 595,453. Renewed August 9, 1916. Serial No. 114,069.

To all whom it may concern:

Be it known that I, GEORGE P. CARROLL, a citizen of the United States, and a resident of Bridgeport, Fairfield county, State of Connecticut, have invented a new and useful Refrigerating-Machine, of which the following is a specification.

My invention relates to improvements in refrigerating machines of the absorption type. My purpose is to construct an automatic machine of the intermittent subtype such that, until the supply of refrigerant in refrigerant reservoir shall have been practically exhausted, a refrigerator thermostat shall control the flow of refrigerant through the expansion coils into the still and the flow of cooling water to the still then acting as an absorber; such that, upon such exhaustion, the flow of refrigerant through the expansion coils and of water to the still shall cease and a heating of the still shall begin; such that upon reaching a predetermined limit the heating of the still shall cease and the control of the machine shall be restored to the refrigerator thermostat; such that any approved means may be employed for condensing the gaseous refrigerant driven off from the still into the refrigerant reservoir; and such that, if during any heating an excessive pressure shall accidentally develop, the heating of the still shall thereupon terminate. My invention includes means for accomplishing these purposes. There are also detail improvements as will appear. The means employed are as will appear.

In the drawings the figure is a diagrammatic representation of my invention.

An inclosed horizontal cylindrical condenser tank 1 has on top, near its right end, an inlet and an elbow 2, for the admission of heated ammonia gas; and has at the bottom, near its left end, an outlet for condensed gas, leading into the upper end of a much smaller liquid ammonia receiver 3, which declines toward its outlet end. A cooling water coil 4 enters the head forming the left end of the tank 1, near the bottom, coils upward through the tank, and emerges through the head near the top of the tank. A small hand valve 5 is connected with the upper side of the elbow 2 and serves as a vacuum valve, or as a charging valve, or as a purge valve, as occasion requires. Connected with the top of the tank 1, near the elbow 2, is a high pressure gage 6. From

the outlet end of the receiver 3 a liquid pipe 7, of an internal diameter of three quarters of an inch or more, leads downward through the top of a refrigerator 8.

From a T 9, connected with a source of cool water supply, a pipe 10 leads to an inlet at the bottom of the casing 11 of a condenser water valve. Above the inlet of the casing 11, and disposed toward it, is a valve seat adapted for the seating of a flat valve 12, opening downward and having a vertical stem 13 extending upward through the casing. The inlet end of the coil 4 leads from the right of the casing 11, above its valve seat. A helical compression spring 14 surrounds the stem 13 above the casing 11 and abuts at its top against the under side of a collar 15 surrounding the stem. By this means the spring 14 tends to lift the valve 12 so as to close the valve. A bracket 16 is bolted to the casing 11 and supports a vertical solenoid 17, having a core 18 secured to the extreme top of the stem 13. The solenoid 17 is so wound that when it is energized it overcomes the thrust of the spring 14 and opens the valve 12. Also supported by the bracket 16 is a horizontal solenoid 19, having a core 20 ending at the left in a stem passing through a yoke at the left of the solenoid and ending at the right in a horizontal arm 21. The arm 21 is adapted to reciprocate through an opening in a part of the bracket 16 and when the valve 12 is closed, as shown, rests against the upper end of the core 18; but when the valve 12 is opened, in consequence of the energization of the solenoid 17, the arm is adapted to slide to the right over the top of the core 18 so as to lock the valve in an open position. A light helical compression spring 22, surrounding the left stem end of the core 20, abuts at its left end against the inside of the yoke referred to and at its right end against a collar on the stem in such a way as to tend to thrust the arm 21 into its locking position. But the solenoid 19 is so wound that, when it is energized, it overcomes the thrust of the spring 22 and draws the arm 21 to the left out of the way of the core 18.

A T 23 is connected to the outlet end of the coil 4. An angle tube 24, open at its upper outer end and closed at its inner lower end, occupies a part of the coil 4 within the upper left part of the tank 1 and extends upward and outward through

the T 23. Surrounding and flaring outward from the open upper end of the tube 24 is a flanged casing 25, inclosed on top by a somewhat flexible diaphragm 26. The 5 thermostatic chamber, composed of the parts 24, 25 and 26, contains a fluid vaporizing at the usual atmospheric temperatures, being preferably anhydrous ammonia with enough liquid to fill that part of the tube 24 within the coil 4. A motor rod 27 has 10 a flanged foot resting on the upper center of the diaphragm 26 and is surrounded just above its foot by a helical outward opposing spring 28. A skeleton top 29, having 15 a perforated and internally threaded central hub around the rod 27, is over the spring 28 and at its outside circumferential rim clamps the diaphragm 26 to the casing 25. A threaded nut 30 surrounds 20 the rod 27 above the spring 28 and screws up or down in the hub of the top 29. By means of the nut 30 the thrust of the spring 28 and consequently the outward movement of the diaphragm 26 are regulated as may 25 be desired. The part of the rod 27 above the top 29 is of reduced diameter and is surrounded by an independently supported collar 31. A light helical inward opposing spring 32 surrounds the rod 27 just above 30 the collar 31. Threaded on to the rod 27 just above the spring 32 is an adjusting nut 33, by means of which the thrust of the spring 32 and consequently the inward movement of the diaphragm 26 are regulated 35 as may be desired. Secured to the extreme top of the rod 27 is a horizontal motor arm 34, extending to the left. The parts 24 to 34 inclusive are sufficient to constitute a condenser thermostat. 40 Supported upon but insulated from a bracket 35, bolted to the top 29, are a lower stationary switch arm 36 and a lower spring switch arm 37. The arm 37 is under the left end of the arm 34 and is above and 45 initially out of contact with the arm 36; but, when the arm 34 is moved a sufficient distance downward, the arm 34 overcomes the spring of the arm 37 and forces the latter into electric contact with the arm 36. 50 Also supported upon but insulated from the bracket 35 are an upper stationary switch arm 38 and an upper spring switch arm 39. The arm 39 is over the left end of the arm 34 and is under and initially 55 out of contact with the arm 38; but, when the arm 34 is moved a sufficient distance upward, the arm 34 overcomes the spring of the arm 39 and forces the latter into electric contact with the arm 38. Main 60 wires 40 and 41 lead respectively to and from a source of electric energy 42. A wire 43 leads from the wire 40 and branches to the arms 37 and 39. A wire 44 leads from the arm 39 to the solenoid 17. A wire 45 65 leads from the solenoid 17 to the wire 41.

A wire 46 leads from the arm 36 to the solenoid 19, and a wire 47 leads from the solenoid 19 to the wire 45.

Connected with the lower end of the pipe 7 within the refrigerator 8 is an automatic expansion valve 48, of the general type shown in the United States patent to me, No. 906,508, dated Dec. 15, 1908. But preferably the valve 48 is the same as is shown in the United States application of Carroll and Roehrich, Ser. No. 542,870, filed Feb. 9, 1910, the latter valve having a downward pocketless course from its inlet to its outlet and having integral with itself a valve strainer in advance of the valve seat. Suitably supported in the upper part of the refrigerator 8 is an open top tank 49, adapted to be nearly filled with calcium chlorid brine, occupying the refrigerator from back to front, but having, between itself and the side walls of the refrigerator, a free passage at the right for the ascending warmer air and a free passage at the left, of the same or a little more width, for the descending chilled air. The right wall 90 of the tank 49 extends upward above the rest of the tank so as to leave, between the top of the wall and the cover of the refrigerator 8, a passage equal to the passage at the right of the tank. An expansion coil 95 51 leads from the valve 48, just above the main part of the tank 49, coils downward through the tank and passes outward, with a slight decline, through the side walls of the tank and of the refrigerator 8. 100

A tube 52, open at its upper outer end and closed at its inner lower end, for most of its length occupies the ascending air space in the refrigerator 8, but extends up through the cover of the refrigerator. Surrounding and flaring outward from the open upper end of the tube 52 is a flanged casing 53, inclosed on top by a somewhat flexible diaphragm 54. The thermostatic chamber, composed of the parts 52, 53 and 54, contains a fluid vaporizing at the usual refrigerator temperatures, being preferably anhydrous ammonia with enough liquid to more or less fill that part of the tube 52 within the refrigerator 8. A motor rod 55 has a flanged foot resting on the upper center of the diaphragm 54 and is surrounded just above its foot by a helical outward opposing spring 56. A skeleton top 57, having a perforated and internally threaded central hub around the rod 55, is over the spring 56 and at its outside circumferential rim clamps the diaphragm 54 to the casing 53. A threaded nut 58 surrounds the rod 55 above the spring 56 and screws up or down in the hub of the top 57. By means of the nut 58 the thrust of the spring 56 and consequently the outward movement of the diaphragm 54 are regulated as may be desired. The part of the rod 55 above the top 57 is of 130

reduced diameter and is surrounded by an independently supported collar 59. A light helical inward opposing spring 60 surrounds the rod 55 just above the collar 59. Threaded on to the rod 55 just above the spring 60 is an adjusting nut 61, by means of which the thrust of the spring 60 and consequently the inward movement of the diaphragm 54 are regulated as may be desired. Secured to the extreme top of the rod 55 is a horizontal motor rod 62, extending to the right. The parts 52 to 62 inclusive are sufficient to constitute a refrigerator thermostat.

Supported upon but insulated from a bracket 63, bolted to the top 57, are a lower stationary switch arm 64 and a lower spring switch arm 65. The arm 65 is under the right end of the arm 62 and is above and initially out of contact with the arm 64; but, when the arm 62 is moved a sufficient distance downward, the arm 62 overcomes the spring of the arm 65 and forces the latter into electric contact with the arm 64. Also supported upon but insulated from the bracket 63 are an upper stationary switch arm 66 and an upper spring switch arm 67. The arm 67 is over the right end of the arm 62 and is under and initially out of contact with the arm 66; but, when the arm 62 is moved a sufficient distance upward, the arm 62 overcomes the spring of the arm 67 and forces the latter into electric contact with the arm 66.

A switch contact 68 is supported by but is insulated from a double solenoid support 69 and is connected with the wire 40. A switch 70 at one end is pivoted upon but is insulated from the support 69 and at its other end is adapted to make or break connection with the contact 68. Supported on the support 69 at the left of the switch 70 is a horizontal left solenoid 71 and at the right of the switch is a horizontal right solenoid 72. Common to the solenoids 71 and 72 is a double end core 73 pivotally connected with the middle of the switch 70, so that when the solenoid 72 is energized the core is pulled to the right to close the switch, as shown, and when the solenoid 71 is energized the core is pulled to the left to open the switch. From the insulated part of the support 69 to which the switch 70 is pivoted, a wire 74 leads and branches to the arms 65 and 67.

55 A vertical cylindrical shell 75, adapted to contain aqua ammonia by a construction more fully explained later, has, within its curved bottom, an electric heating member 76, containing high resistance wires 77, doubly wound, so as to be non-inductive. Through the member 76 are numerous vertical openings 78, so that heat from the wires may be readily transmitted to the contents of the shell 75. The member 76 is also surrounded by a free space on all sides except

that it has a stem 79 passing through the bottom of the shell 75. Formed on the outside of the shell 75 is a stuffing box 80, containing an annular packing 81 around the stem 79. A stuffing gland 82 surrounds the stem 79 and is screwed into the stuffing box 80 so as to compress the packing 81. By this means leakage is prevented around the stem 79. A feed wire 83 leads to the wires 77 through the stem 79 and a return wire 84 leads from them through the stem to the wire 41.

It is to be understood that, owing to the strong corrosive effect of ammonia, neither copper nor any of its alloys are to come in contact with ammonia, whether anhydrous or in solution. Consequently the wires 77 are inclosed in the members 76, made of iron or steel and glass enameled in the manner to be described, and are surrounded within the member by heat transmitting material such as is usual in electric heaters.

Passing through the side of the shell 75 is a gas inlet pipe 85, with a slight inward decline, ending in the upper end of a vertical pipe 86, having a very widely flaring discharge end immediately above the member 76. A hand valve 87, outside the shell 75, may be used, on occasion, to shut off the pipe 85. Also passing through the side of the shell 75, above the pipe 85, is the inlet end of a helical cooling coil 88, surrounding the pipe 86 and emerging from the side of the shell a little distance above the member 76. A cover 89 is secured to the flanged top of the shell 75.

An expansion coil outlet valve structure 90 has the inlet of its lower casing 91 connected with the outside and lower end of the coil 88 and has the outlet of its lower casing connected with the inlet end of a slightly descending pipe 92, coupled to the inlet end of the pipe 85. The course through the casing 91 is downward; and between its inlet and outlet is a valve seat adapted for the seating of a flat valve 93, opening downward toward the outlet of the casing and having a vertical stem 94 extending upward toward the top of the casing. The upper end of the stem 94 is secured to the center of a somewhat flexible diaphragm 95, which has an inside exposed surface a little larger than the opposite exposed surface of the valve 93. An upper casing 96 is bolted to the top of the casing 91 so as to tightly clamp the circumference of the diaphragm 95 between the two casings. It will be noted that by this construction there is a slight tendency for fluid under pressure, emerging from the coil 88, to close the valve 93 on its seat; and that back pressure through the pipes 86, 85 and 92 tends to so close the valve 93, the tendency to close increasing as the back pressure increases. It will be further noted that the downward course of the refrigerant from

the elbow 2 to the end of the pipe 86 is pocketless.

Bolted to the top of the casing 96 is a solenoid yoke 97, holding in place, supported upon the casing, a vertical solenoid 98. A core 99 is adapted to reciprocate within the solenoid 98, has a lower stem extension passing through an opening in the top of the casing 96 and secured to the top of the diaphragm 95, and has an upper stem extension passing through an opening in the top of the yoke 97 and threaded at its upper end. A helical compression spring 100 surrounds the upper stem extension of the core 99, above the yoke 97, and abuts at its top against the under side of a collar 101 threaded on to the extension. By this means the spring 100 adds force to the diaphragm 95 in tending to lift the valve 93 and its tendency in so doing can be regulated by the collar 101. The solenoid 98 is so wound that when it is energized it overcomes the diaphragm 95 and the spring 100 and lowers the valve 93 so as to open the valve. A horizontal cross arm 102 is secured to the extreme top of the upper stem extension of the core 99. Supported by a bracket extending from the yoke 97 is a double end solenoid yoke 103, supporting between its ends a horizontal solenoid 104. A core 105 is adapted to reciprocate within the solenoid 104, has a right stem extension passing through an opening in the right end of the yoke 97, and has a left stem extension passing through the left end of the yoke. A helical compression spring 106 surrounds the left stem extension of the core 105 to the right of the left end of the yoke 103 and at its right abuts against a collar on the extension. When the valve 93 is elevated, as shown, the extreme right end of the right stem extension of the core 105 abuts against the left end of the arm 102, as shown; when an energization of the solenoid 98 depresses the valve 93, the spring 106 forces the extreme right end of the right stem extension of the core 105 over the arm 102 so as to lock the valve in an open position after the energization of the solenoid 98 has ceased; the solenoid 104 is so wound that, when it is energized, it overcomes the spring 106 so as to draw the core 105 to the left, releasing the arm 102 and permitting the spring 100 to close the valve; and finally, when the solenoid 104 is no longer energized, the spring 106 forces the core 105 into its initial position. From the arm 66 a wire 107 leads to the solenoid 98; and from this solenoid a wire 108 leads to the wire 41. From the arm 64 a wire 109 leads to the solenoid 104; and from this solenoid a wire 110 leads to the wire 108.

A branch water pipe 111 leads from the T 9 to an inlet at the bottom of the casing 112 of a water inlet valve, to the right of the valve structure 90. Above the inlet of

the casing 112, and disposed toward it, is a valve seat adapted for the seating of a flat valve 113, opening downward and having a vertical stem 114 extending upward through the valve casing. A pipe 115 leads from the right of the casing 112, above its valve seat, slightly descends and is coupled to the inlet end of the coil 88. A helical compression spring 116 surrounds the stem 114 above the casing 112 and abuts at its top against the under side of a collar 117 surrounding the stem. By this means the spring 116 tends to lift the valve 113 so as to close the valve. The upper end of the stem 114 passes through and is guided by a bracket 118, bolted at its lower end to the casing 112, and has secured to its extreme top a horizontal cross arm 119 extending under the arm 102. By this means, when the arm 102 is depressed, the arm 119 and the valve 113 are also depressed so as to open the valve 112, and when the arm 102 is lifted, the spring 116 lifts the valve 113 and closes the valve 112.

A double solenoid support 120 supports a switch contact 121, connected with the wire 40, and an opposite switch contact 122, connected with the wire 83, both contacts being insulated from the support. Supported on the support 120 at the left of the contacts 121 and 122 is a horizontal left solenoid 123 and at the right of these contacts is a horizontal right solenoid 124. Common to the solenoids 123 and 124 is a double end core 125, carrying a cross bar switch 126, which makes contact with the contacts 121 and 122 when the solenoid 123 is energized and breaks contact with them, as shown, when the solenoid 124 is energized.

A thermostatic tube 127, open at its upper end and closed at its lower end, projects downward through the cover 89 so far into the shell 75 that, for a part of its length, while the machine is in operation, the tube 110 will be immersed in the aqua ammonia contained in the still. Surrounding and flaring outward from the open upper end of the tube 127 is a flanged casing 128, inclosed on top by a somewhat flexible diaphragm 129. The thermostatic chamber, composed of the parts 127, 128 and 129, contains an expansive fluid, preferably ethyl chlorid which vaporizes at about 54° F. A motor rod 130 has a flanged foot resting on the upper center of the diaphragm 129 and is surrounded just above its foot by a helical outward opposing spring 131. A skeleton top 132, having a perforated and internally threaded central hub around the rod 130, is over the spring 125 131 and at its outside circumferential rim clamps the diaphragm 129 to the casing 128. A threaded nut 133 surrounds the rod 130 above the spring 131 and screws up or down in the hub of the top 132. By means of the 130

nut 133 the thrust of the spring 131 and consequently the outward movement of the diaphragm 129 are regulated as may be desired. The part of the rod 130 above the top 132 5 is of reduced diameter and is surrounded by an independently supported collar 134. A light helical inward opposing spring 135 surrounds the rod 130 just above the collar 134. Adjustably threaded on to the extreme 10 top of the rod 130 is a horizontal cross arm 136, extending to the right. By adjusting the longitudinal position of the arm 136 the thrust of the spring 135 and consequently the inward movement of the diaphragm 129 15 are regulated as may be desired. The parts 127 to 136 inclusive are sufficient to constitute a still thermostat.

A high pressure pipe 137 leads outward and upward from the upper part of the shell 20 75 into the bottom of a flanged casing 138, inclosed on top by a somewhat flexible diaphragm 139. A motor rod 140 has a flanged foot resting on the upper center of the diaphragm 139 and is surrounded just above 25 its foot by a helical outward opposing spring 141. A skeleton top 142, having a perforated and internally threaded hub around the rod 140, is over the spring 141 and at its outward circumferential rim clamps the diaphragm 139 to the casing 138. A threaded nut 143 surrounds the rod 140 above the spring 141 and screws up or down in the hub of the top 142. By means of the nut 143 30 the thrust of the spring 141 and consequently the outward movement of the diaphragm 139 are regulated as may be desired. Adjustably threaded on to the extreme top of the rod 140 is a horizontal cross arm 144, extending to the left and almost to the right 35 end of the arm 136. The parts 137 to 144 inclusive are sufficient to constitute a high pressure safety device.

A suitably supported vertical sleeve 145 has within it a reciprocating motor rod 146, 40 having at its lower end a disk immediately over the adjacent ends of the arms 136 and 144. A light helical spring 147 surrounds the rod 146 above its disk and below the sleeve 145 so as to cause the rod to follow 45 the arms 136 and 144 on a downward movement by them. Adjustably threaded on to the extreme top of the rod 146 is a horizontal motor arm 148, extending to the left. Supported upon but insulated from 50 a bracket 149, integral with the sleeve 145, are a lower stationary switch arm 150 and a lower spring switch arm 151. The arm 151 is under the left end of the arm 148 and is above and initially cut out of contact 55 with the arm 150; but, when the arm 148 is moved a sufficient distance downward, the arm 148 overcomes the spring of the arm 151 and forces the latter into electric contact with the arm 150. Also supported 60 upon but insulated from the bracket 149

are an upper stationary switch arm 152 and an upper spring switch arm 153. The arm 153 is over the left end of the arm 148 and is under and initially out of contact with the arm 152; but, when the arm 148 is 65 moved a sufficient distance upward, the arm 148 overcomes the spring of the arm 153 and forces the latter into electric contact with the arm 152. A wire 154 leads from the wire 40 and branches to the arms 151 70 and 153. A wire 155 leads from the arm 152 to the solenoid 124; and from this solenoid a wire 156 leads to the wire 41. A wire 157 leads from the arm 150 to the solenoid 72; and from this solenoid a wire 80 158 leads to the wire 41.

A T 159 is connected with the outside lower end of the coil 88. From the under side of the T 159 a pipe 160 leads to a T 161. A hand valve 162 controls the pipe 85 160 and is used to determine the quantity of flow through the coil 88 when the valve 112 is open, the idea being to let the water scarcely more than trickle from the coil. From the T 161 a pipe 163 leads to an outlet T 164, connected with the waste. 90

The upper part of the casing 165 of a water outlet valve is connected with the T 159 as an inlet and the lower part of the casing is connected with the T 161 as an 95 outlet. Between the inlet and outlet of the casing 165 and disposed toward the outlet, is a valve seat adapted for the seating of a flat valve 166, opening downward and having a vertical stem 167 extending upward through the valve casing. Bolted to the top of the casing 165 is a solenoid yoke 168, holding in place, supported upon the casing, a vertical solenoid 169. A core 170 is adapted to reciprocate within the solenoid 169, is secured to the top of the stem 167, 100 and has an upper stem extension passing through an opening in the top of the yoke 168, with a catch disk 171 secured to its top. A helical compression spring 172 surrounds the upper stem extension of the core 170, above the yoke 168, and abuts at its top on the under side of a collar 173 surrounding the extension under the valve 171. The spring 172, acting on the collar 173, 105 tends to lift the core 170, the stem 167 and the valve 166 so as to close the valve. But the solenoid 169 is so wound that when it is energized, acting on the core 170, it overcomes the spring 172 and opens the valve 166. Supported by a bracket extending from the yoke 168 is a solenoid yoke 174, supporting a horizontal solenoid 175. A core 176 is adapted to reciprocate within the solenoid 175, has a right stem extension 110 passing through the right end of the yoke 174, and has a left stem extension passing through the left end of the yoke. A helical compression spring 177 surrounds the right stem extension of the core 176 to the left 115 120 125 130

of the right end of the yoke 174 and at its left end abuts against a collar on the extension. When the valve 166 is elevated, as shown, in which case the valve is closed, 5 the extreme left end of the left stem extension of the core 176 abuts against the valve, as shown; when an energization of the solenoid 169 depresses the valve 166, the spring 177 forces the extreme left end of the core 10 176 over the disk 171 so as to lock the valve in an open position after the energization of the solenoid 169 has ceased; the solenoid 175 is so wound that, when it is energized, it overcomes the spring 177 so as to draw 15 the core 176 to the right, releasing the disk 171 and permitting the spring 172 to close the valve; and finally, when the solenoid 175 is no longer energized, the spring 177 forces the core 176 into its initial position. 20 A wire 178 leads from the wire 157 to the solenoid 175. A wire 179 leads from the solenoid 175 and joins a wire 180 which leads from the solenoid 169 to the wire 41. Threaded into an opening in the cover 25 89 is the lower member 181 of a check valve casing having an outwardly disposed valve seat. Seated on the valve seat of the member 181 is a check valve 182, opening outward and upward and having an upwardly 30 extending stem surrounded by a very light helical spring 183. The upper member 184 of the valve casing bears upon the top of the spring 183, has an opening which the stem of the valve 182 occupies so loosely as to leave 35 sufficient space for ascending gas, and at its flanged lower edge is bolted to the member 181. A hand valve casing 185 is threaded on to the member 184, has a coupling thread around its upper end and is provided with 40 a hand valve 186. By means of the valves 87 and 186 the still may be shut off from the rest of the machine, if occasion so requires. Coupled to the casing 185 is an upwardly 45 ascending pipe and elbow connection 187. Slightly ascending from the elbow end of the connection 187 is a pipe 188 which leads into the elbow 2. Just as there is a pocketless downward course from the elbow 2 through the expansion chamber into the shell 50 75, so there is a pocketless upward course from the shell 75, for ascending gas, into the elbow. Consequently there is no place in the machine for the lodgment of entrained water. From the T 23 a pipe 189 leads into 55 the higher end of a cylindrical casing 190 surrounding the pipe 188, the place of entrance being near the elbow 2. From the lower end of the casing 190, near the connection 187, a pipe 191 leads to the T 164 60 and is provided with a hand valve 192 which is used to determine the quantity of flow through the coil 4. The pipe 188 and the casing 190 are sufficient to constitute a dehydrator, although it is more usual to arrange 65 the parts so that the descending water will

flow through the inner pipe and the ascending gas will pass through the outer annular space.

Connected with the top of the tank 1 is a flanged casing 193, inclosed on top by a somewhat flexible diaphragm 194. A motor rod 195 has a flanged foot resting on the upper center of the diaphragm 194 and is surrounded just above its foot by a helical outward opposing spring 196. A skeleton top 70 197, having a perforated and internally threaded hub around the rod 195, is over the spring 196 and at its outside circumferential rim clamps the diaphragm 194 to the casing 193. A threaded nut 198 surrounds the rod 195 above the spring 196 and screws up or down in the hub of the top 197. By means of the nut 198 the thrust of the spring 196 and consequently the inward movement of the diaphragm 194 are regulated as may be 80 desired. Adjustably threaded on to the extreme top of the rod 195 is a horizontal cross arm 199, extending to the right. The parts 85 193 to 199 inclusive are sufficient to constitute a starter.

Supported upon but insulated from a bracket 200, bolted to the top 197 are a stationary switch arm 201 and a spring switch arm 202. The arm 202 is under the right end of the arm 199 and is above and initially 90 out of contact with the arm 201; but, when the arm 199 is moved a sufficient distance downward, the arm 199 overcomes the spring of the arm 202 and forces the latter into electric contact with the arm 201. From the wire 40 a wire 203 leads to the arm 202. From the contact 201 a wire 204 leads to the solenoid 169. From the wire 204 a wire 205 leads to the solenoid 71; and from this solenoid a wire 206 leads to the wire 41. From the wire 204 a wire 207 leads to the wire 109. From the wire 204 a wire 208 leads to the solenoid 123; and from this solenoid a wire 209 leads to the wire 41. 100 105

A thermometer 210 extends downward 110 through the cover 89 so as to have its lower end immersed in the aqua ammonia in the still.

The method of operation is as follows: A back gage pressure of 15 lbs. denotes a 115 temperature of 0° F. in an expansion coil. But in a refrigerator 8, of the character indicated, so low a temperature in the coil 51 would probably not be desired. Hence the absorption in the shell 75 will take place under a back pressure in excess of 15 lbs. But under a pressure of 15 lbs. a solution of aqua ammonia can contain 38 per cent. by weight of ammonia up to a temperature of 104° F. Hence enough distilled water is introduced 120 into the shell 75, through the valve 5 or preferably through a closable opening in the cover 89, so that, when the water receives enough ammonia to form a 38 per cent. solution, the shell 75 will be about four-fifths 125 130

full. The valves 87 and 186 being open, the valve 48, from its known construction, being also open, and the valve 93 being temporarily opened by hand, as many inches of vacuum 5 are pumped through the valve 5 as are practicable. By this means not merely is the free air largely exhausted from the refrigerant circuit; but also the air in the water in the shell 75 rises to the surface and is 10 pumped out. After closing the valve 93, a quantity of anhydrous ammonia is then slowly introduced through the valve 5 sufficient to make the 38 per cent. solution when all of the ammonia shall eventually reach 15 the shell 75. The advancing ammonia creates a pressure in the coil 51 that closes the valve 48. The bulk of the ammonia then occupies the receiver 3, the pipe 7 and the valve 48 in advance of its seat. Ammonia 20 vapor also presses the valve 182 more closely to its seat. After the machine has been allowed to stand for a while, the residual air rises to the top and may be purged off through the valve 5.

25 Various adjustments are made as follows: The spring 28 is so adjusted that the arm 34 will force the arm 39 into contact with the arm 38 when the ammonia pressure in the thermostatic chamber of the parts 24, 30 25 and 26 rises say to 183 lbs., as indicated by the gage 6, corresponding to a temperature in the coil 4 of 95°. And the spring 32 is so adjusted that the arm 34 will force the arm 37 into contact with the arm 36 35 when the pressure in that chamber falls say to 139 lbs., as indicated by the gage 6, corresponding to a temperature of 80° in the coil. Also the spring 196 is so adjusted that the arm 199 will force the arm 102 40 into contact with the arm 101 when the pressure in the tank 1 drops say to 30 lbs. The pressure limit of 30 lbs. is taken because, with a proper initial charge of ammonia, the water in the shell 75 would continue to absorb ammonia until the pressure in the tank 1 had dropped to and below that limit. The valve 48 is so adjusted as to prevent a pressure in excess say of 25 lbs. in the coil 51. This pressure corresponds to a 50 vaporizing temperature in the coil of 12° and will produce a temperature in the brine tank of only a few degrees higher. Assume the temperature to be maintained in the refrigerator 8 is to be between the limits of 55 35° and 38°. Then the spring 56 is so adjusted that the arm 62 will force the arm 67 into contact with the arm 66 when the ammonia pressure in the thermostatic chamber of the parts 52, 53 and 54 rises to 55 lbs., 60 corresponding to a temperature of 38°. And the spring 60 is so adjusted that the arm 62 will force the arm 65 into contact with the arm 64 when the pressure in that chamber falls to 51 lbs., corresponding to a temperature of 35°. Also the spring 131 is so

adjusted that the arms 136 and 148 will force the arm 153 into contact with the arm 152 when the fluid pressure in the thermostatic chamber of the parts 127, 128 and 129 rises to a pressure corresponding say to a 70 temperature of 280° in the still. And the spring 135 is so adjusted that the spring 147 will cause the arm 148 to force the arm 151 into contact with the arm 150 when the fluid pressure in that chamber falls to a pressure 75 corresponding say to a temperature of 110° in the still. It is not necessary to know what will be these two pressure limits of the fluid vapor. For the proper spring adjustments to produce the two actions of the arm 148 are 80 determined by trial at the two temperature limits in the still, as observed by the thermometer 210. And the spring 141 is so adjusted that the arms 144 and 148 will force the arm 153 into contact with the arm 152 85 when, if it so happens, the pressure in the still rises say to 220 lbs.

Now assume that water is free to flow through the T 9, that a current from the wires 40 and 41 is available, and that the 90 temperature in the refrigerator 8 rises to 38°. Thereupon the arm 62 forces the arm 67 into contact with the arm 66 and a current passes from the wire 40 through the parts 68, 70, 74, 67, 66, 107, 98 and 108 back 95 to the wire 41. The consequent energization of the solenoid 98 opens the valves 93 and 113. The ammonia gas in the coil 51 now passes through the valve 93 and the pipes 92, 85 and 86 and is absorbed by the 100 water in the shell 75. Liquid ammonia passes the valve 48, vaporizes in the coil 51 and cools the brine. Water flows through the pipe 111, the valve 113 and the pipe 115 into the coil 88 and passes out through the 105 T 159, the pipe 160, the T 161, the pipe 163 and the T 164. The flow of water through the coil 88 takes away the heat given off by the ammonia as it is absorbed in the shell 75. The opening in the valve 48 is such as to 110 permit a flow of enough ammonia to frost the coil 51 to the outside of the tank 49. The chilled air over the tank 49 descends within the refrigerator 8 along the inside of its left wall and the warmer air rises past the 115 tube 52 over the wall 50. With the fall of temperature the arm 62 drops and the arm 67 springs away from the arm 66. After a while the temperature in the refrigerator 8 drops to 35°. Thereupon the arm 62 120 forces the arm 65 into contact with the arm 64 and a current passes from the wire 40 through the parts 68, 70, 74, 65, 64, 109, 104, 110 and 108 back to the wire 41. The consequent energization of the solenoid 104 125 draws the core 105 to the left and the valves 93 and 113 close. With the closing of the valve 93 pressure accumulates in the coil 51 and closes the valve 48. The brine in the tank 49 keeps the refrigerator cool for some 130

hours after the vaporization of ammonia through the valve 48 has ceased.

These cycles of opening and closing of the valves 93 and 113 continue as long as any liquid ammonia remains in the refrigerant reservoir. As the last of the liquid passes through the valve 48, vaporization takes place in advance of the valve seat. But as the pipe 7 is several inches long and of the 10 diameter stated, the refrigerating effect is produced within the refrigerator 8, rather than outside of it. While any liquid remains in the refrigerant reservoir, the pressure in the starter is precisely that which 15 corresponds to the temperature outside of the pipe 7 at its coldest part; and, in the condition assumed of an operation of the machine to maintain a low temperature limit of 35° in the refrigerator 8, the pressure remains above 51 lbs. But, just after the last 20 of the liquid ammonia has passed through the valve 48, the ammonia in the refrigerant reservoir no longer is a vapor but is a gas. As a gas the pressure of this ammonia 25 depends upon its density exclusively. The passage of some of this gas through the valve 48 diminishes the density and pressure of the remaining gas in the refrigerant reservoir until finally the pressure in the starter 30 drops to 30 lbs. Thereupon the arm 199 forces the arm 202 into contact with the arm 201. A current now passes from the wire 40 through the parts 203, 202, 201 and the wire 204 by several branches back to the 35 wire 41. One branch current from the wire 204 passes through the parts 205, 71 and 206. The consequent energization of the solenoid 71 opens the switch 70 and makes the refrigerator thermostat inoperative for 40 the time being. Another branch current passes from the wire 204 through the parts 207, 109, 104, 110 and 108 back to the wire 41. The consequent energization of the solenoid 104 draws the core 105 to the left so as 45 to close the valves 93 and 113 if they are open. Another branch current passes from the wire 204 through the parts 208, 123 and 209. The consequent energization of the solenoid 123 closes the switch 126 and permits the passage of a current from the wire 40 50 through the parts 121, 126, 122, 83, 77 and 84 back to the wire 41. The member 76 being thus heated, the heating of the contents of the shell 75 begins. And another 55 branch current passes from the wire 204 through the parts 169 and 180 back to the wire 41. The consequent energization of the solenoid 169 opens the valve 166 and lets the water flow from the coil 88 more 60 rapidly than it could flow through the valve 162 alone.

As the contents of the shell 75 is heated ammonia gas is driven off, overcoming the slight resistance of the valve 182, and passes 65 through the parts 181, 184, 187, 188 and 2

into the tank 1. It will be noted that as the condenser pressure rises, the arm 199 moves upward and the arm 202 breaks contact with the arm 201. This is as it should be, for the starter has completed its work. The 70 heated gas in the tank 1 soon raises the temperature of the water in the coil 4 to 95°. Thereupon the arm 34 forces the arm 39 into contact with the arm 38. And a current then passes from the wire 40 through the 75 parts 43, 39, 38, 44, 17 and 45 back to the wire 41. The consequent energization of the solenoid 17 opens the valve 12 and permits water to flow through the parts 4, 189, 190, 191, 192 and 164. The water flowing in the 80 coil 4 condenses and liquefies the ammonia coming into the tank 1 and the water flowing downward in the casing 190 cools the ascending ammonia to such an extent that nearly all of the entrained water vapor is 85 condensed and flows back as water into the shell 75. As fast as it is condensed, the liquefied ammonia drops to the bottom of the refrigerant reservoir. The valve 11 continues open until the temperature in the 90 coil 4 drops to 80°. Thereupon the arm 34 forces the arm 37 into contact with the arm 36. And a current then passes from the wire 40 through the parts 43, 37, 36, 46, 19, 47 and 45 back to the wire 41. The consequent 95 energization of the solenoid 19 draws the arm 21 to the left and the valve 12 closes. The closing of the valve 12 may not take place until after the heating of the shell 75 has terminated or it may occur several times in 100 each heating. Furthermore if the atmospheric temperature rises above 95°, the valve 12 may operate at any time. It will thus be seen that the automatic condenser, that is shown and described, is entirely independent in its operation of the other parts 105 of the machine.

Under the conditions assumed the heating of the shell 75 normally continues until its temperature reaches 280°. At that temperature, the percentage of ammonia in the solution in the shell 75, which at the beginning of the heating was 38 per cent., is reduced to about 20 per cent., if the temperature in the tank 1 is at 95°, which corresponds to a 110 head pressure of 184 lbs., as indicated by the gage 6. Or the percentage of ammonia in the solution is reduced to about 16 per cent., if the temperature in the condenser is at 80°, which corresponds to a head pressure of 140 115 lbs. as indicated by the gage 6. Or the percentage of ammonia in the solution is reduced to some percentage between 16 and 20, if the temperature of the still reaches 280° when the temperature in the condenser is at 120 some point between 80° and 95°. In any 125 such case, however, at the limit of 280°, the arms 136 and 148 force the arm 153 into contact with the arm 152. And a current then passes from the wire 40 through the parts 130

154, 153, 152, 155, 124 and 156 back to the wire 41. The consequent energization of the solenoid 124 opens the switch 126 and breaks the current to the wires 77 so as to terminate the heating of the contents of the shell 75. Obviously the chances of reducing the percentage of ammonia in the solution, at the normal end of the heating of the contents of the shell 75, toward the low limit of 16 per cent. is increased if the spring 28 is adjusted so that the valve 12 opens at a condenser temperature of 90°, which corresponds to a pressure of 168 lbs. as indicated by the gage 6. The only disadvantage in lowering the opening limit of the valve 12 is that, with this type of automatic condenser, there will be a greater flow of water in summer weather ranging above 90°. So also the percentage of ammonia remaining in the solution at the normal end of the heating may be much reduced by making the heating limit to be some higher limit than 280°, say 300°. At 300°, with a head pressure of 184 lbs., corresponding to 95°, the percentage of ammonia in the solution is reduced to about 15 per cent.; with a head pressure of 168 lbs., corresponding to 90°, such percentage is reduced to about 14 per cent.; and with a head pressure of 140 lbs., corresponding to 80°, such percentage is reduced to about 11 per cent. Of course a higher heating limit requires more fuel and an increased amount of water vapor is driven over, most of it indeed coming back through the dehydrater, but some of it passing into the refrigerant reservoir and coming back through the coil 51.

Sometimes by accident there is a failure of condensing water. With a very slow heating of the contents of the shell 75, too slow for practical purposes, the ammonia driven off from the shell 75 might give off its heat in the tank 1 by radiation and so become liquefied. But with a heating of the contents of the shell 75 at the usual rate of increase of the heat, a failure of condensing water results in a quick rise of temperature in the tank 1 and of pressure in all the passages reaching back to the shell 75. If the temperature of the liquid ammonia in the refrigerant reservoir should rise to 105°, the pressure of the vapor in contact with it would be 218 lbs. and the pressure of the gas in the upper part of the shell 75 would be quite a number of pounds higher. Hence the limit of 220 lbs. is fixed as that at which the high pressure safety device is to act. Assume now that, owing to a failure of condensing water, the pressure in the shell 75 rises to 220 lbs. Thereupon the arms 144 and 148 force the arm 153 into contact with the arm 152 and there is the same termination of the heating of the contents of the shell 75 as before, except that the percentage of ammonia remaining in the solution is more or

less greater than in case of a normal termination.

In either case, when the heating of the contents of the shell 75 ceases, the temperature in the shell 75 begins to fall. As the temperature falls, the pressure rapidly drops, the valve 182 having meantime closed. When the temperature of the contents of the shell 75 has fallen to 110° these are only a few pounds pressure in the shell 75 and it is ready to again act as an absorber. At the low limit of 110° the arm 148 forces the arm 151 into contact with the arm 150. And a current then passes from the wire 40 through the parts 154, 151, 150, 157, 72 and 158 back to the wire 41. The consequent energization of the solenoid 72 closes the switch 70 and restores the control of the machine to the refrigerator thermostat. Also a branch current from the wire 157 passes through the parts 178, 175, 179 and 180 back to the wire 41. The consequent energization of the solenoid 175 draws the core 176 to the right and permits the valve 166 to close. Consequently the flow of water through the coil 88 is again throttled by the valve 162. The major cycle of operation, involving the heating of the shell 75, is thus complete.

It is evident that, while in one sense the tank 1 constitutes a condenser, yet, in a larger sense, the term condenser includes all the conduits through which the refrigerant passes between the valve 182 and the valve 48 and also includes the water conduits associated with these refrigerant conduits. The broad term evaporator comprehends all the conduits through which the refrigerant passes between the valve 48 and the valve 93. The term still comprehends, not merely the shell 75, but in addition the conduits through which the refrigerant passes between the valve 93 and the valve 182 and also the water conduits leading from the casing 112 through the shell 75. The term thermostat broadly includes all the connections whereby it is operative.

What I have invented and what I desire to have protected by Letters Patent is expressed in claims as follows:

I claim:

1. In combination a condenser, an evaporator leading from said condenser, a still adapted to contain an absorbent and leading from said evaporator into said condenser, means for preventing a back flow of refrigerant from said condenser into said still and from said still into said evaporator, means for regulating the expansion of refrigerant from said condenser into said evaporator and its absorption in said still, and means operating when the pressure in said condenser falls to a predetermined limit to heat said still.

2. In combination a condenser, an evaporator leading from said condenser, a still

adapted to contain an absorbent and leading from said evaporator into said condenser, means for preventing a back flow of refrigerant from said condenser into said 5 still and from said still into said evaporator, means for regulating the expansion of refrigerant from said condenser into said evaporator and its absorption in said still, and means controlled by the pressure of 10 refrigerant in said condenser and operating when such pressure falls to a predetermined limit to heat said still to a predetermined limit.

3. In combination a condenser, an evaporator leading from said condenser, a still 15 adapted to contain an absorbent and leading from said evaporator into said condenser, means for preventing a back flow of refrigerant from said condenser into said 20 still and from said still into said evaporator, means for regulating the expansion of refrigerant from said condenser into said evaporator and its absorption in said still, means operating when the pressure in said 25 condenser falls to a predetermined limit to heat said still normally to one predetermined limit, and a safety device operating to stop such heating in case the pressure in said still, before such normal termination, 30 rises above a normal limit.

4. In combination a condenser, an evaporator leading from said condenser, a still adapted to contain an absorbent and leading from said evaporator into said condenser, means for preventing a back flow of refrigerant from said condenser into said still and from said still into said evaporator, means for regulating the expansion of refrigerant from said condenser into said 35 evaporator and its absorption in said still, means controlled by the pressure of refrigerant in said condenser and operating when such pressure falls to a predetermined limit to heat said still normally to one predetermined limit, and a safety device operating to stop such heating in case the pressure in said still in the time of heating rises above a normal limit.

5. In combination a condenser, an evaporator leading from said condenser through a place to be refrigerated, a still adapted to contain an absorbent and leading from said evaporator into said condenser, means for preventing a back flow of refrigerant from said condenser into said still and from said still into said evaporator, dominating means operating when the pressure in said condenser falls to a predetermined limit to heat said still, and refrigerant 55 regulative means temperature controlled in the period between the operations of said dominating means and then operative to regulate the expansion of refrigerant from said condenser into said evaporator and its absorption in said still so as to maintain a predetermined temperature in said place, said dominating means during such heating also causing said regulative means to be inoperative.

predetermined temperature in said place, said dominating means during such heating also causing said regulative means to be inoperative.

6. In combination a condenser, an evaporator leading from said condenser through a place to be refrigerated, a still adapted to contain an absorbent and leading from said evaporator into said condenser, means for preventing a back flow of refrigerant from said condenser into said still and from said still into said evaporator, dominating means controlled by the pressure of refrigerant in said condenser and operating when such pressure falls to a predetermined limit to heat said still to a predetermined limit, and refrigerant regulative means temperature controlled in the period between the operations of said dominating means and then operative to regulate the expansion of refrigerant from said condenser into said evaporator and its absorption in said still so as to maintain a predetermined temperature in said place, said dominating means during such heating also causing said regulative means to be inoperative.

7. In combination a condenser, an evaporator leading from said condenser through a place to be refrigerated, a still adapted to contain an absorbent and leading from said evaporator into said condenser, means for preventing a back flow of refrigerant from said condenser into said still and from said still into said evaporator, dominating means operating when the pressure in said condenser falls to a predetermined limit to heat said still normally to one predetermined limit, a safety device operating to stop such heating in case the pressure in said still, before such normal limitation, rises above a normal limit, and refrigerant regulative means temperature controlled in the period between the operations of said dominating means and then operative to regulate the expansion of refrigerant from said condenser into said evaporator and its absorption in said still so as to maintain a predetermined temperature in said place, said dominating means during such heating also causing said regulative means to be inoperative.

8. In combination a condenser, an evaporator leading from said condenser through a place to be refrigerated, a still adapted to contain an absorbent and leading from said evaporator into said condenser, means for preventing a back flow of refrigerant from said condenser into said still and from said still into said evaporator, dominating means controlled by the pressure of refrigerant in said condenser and operating when such pressure falls to a predetermined limit to heat said still normally to a high temperature limit, a safety device operating to stop

such heating in case the pressure in said still in the time of heating rises above a normal limit, and refrigerant regulative means temperature controlled in the period between 5 the operations of said dominating means and then operative to regulate the expansion of refrigerant from said condenser into said evaporator and its absorption in said still so as to maintain a predetermined temperature 10 in said place, said dominating means during such heating also causing said regulative means to be inoperative.

9. In combination a condenser, an evaporator leading from said condenser through 15 a place to be refrigerated, a still adapted to contain an absorbent and leading from said evaporator into said condenser, means for preventing a back flow of refrigerant from said condenser into said still and from 20 said still into said evaporator, means for heating at intervals said still, means for permitting a flow of cooling water at intervals to said condenser and to said still, and means for utilizing temperature and pressure 25 conditions in said still and condenser to control such heating and cooling operations and to maintain a predetermined temperature in said place.

10. In combination a condenser, an evaporator leading from said condenser, a still adapted to contain an absorbent and leading from said evaporator into said condenser, means for preventing a back flow of refrigerant from said condenser into said still and from said still into said evaporator, means for heating at intervals said still, means for permitting a flow of cooling water at intervals to said condenser and to said still, and means for utilizing temperature 40 and pressure conditions in said still and condenser to control such heating and cooling operations.

11. In combination a condenser, an evaporator leading from said condenser, a still adapted to contain an absorbent and leading from said evaporator into said condenser, means for preventing a back flow of refrigerant from said condenser into said still, an automatic expansion valve controlling 45 the inlet end of said evaporator, a stop valve controlling the outflow from said evaporator, and means operative at intervals for closing said stop valve if open and for heating said still.

55 12. In combination a condenser, an evaporator leading from said condenser, a still adapted to contain an absorbent and leading from said evaporator into said condenser, means for preventing a back flow of refrigerant from said condenser into said still, an automatic expansion valve controlling 60 the inlet end of said evaporator, a stop valve controlling the outflow from said evaporator, and means operating when the pressure 65 in said condenser falls to a predetermined

limit to close said stop valve if open and to heat said still.

13. In combination a condenser, an evaporator leading from said condenser, a still adapted to contain an absorbent and leading from said evaporator into said condenser, means for preventing a back flow of refrigerant from said condenser into said still, an automatic expansion valve controlling the inlet end of said evaporator, a stop valve controlling the outflow from said evaporator, a thermostat controlled by the temperature about said evaporator and controlling said stop valve, means operative at intervals, for closing said stop valve if open, 70 for suspending the operativeness of said thermostat and for starting a heating of said still, means operative to terminate such heating at a predetermined limit, and means restoring the operativeness of said thermostat 75 after such heating.

14. In combination a condenser, an evaporator leading from said condenser, a still adapted to contain an absorbent and leading from said evaporator into said condenser, means for preventing a back flow of refrigerant from said condenser into said still, an automatic expansion valve controlling the inlet end of said evaporator, a stop valve controlling the outflow from said evaporator, a thermostat controlled by the temperature about said evaporator and controlling said stop valve, means operating 90 when the pressure in said condenser falls to a predetermined limit to close said stop valve if open, to suspend the operativeness of said thermostat and to start a heating of said still, means operative to terminate such heating at a predetermined limit, and means restoring the operativeness of said thermostat 95 after such heating.

15. In combination a refrigerant reservoir, a still adapted to contain an absorbent, an expansion chamber leading from said reservoir to said still, a conduit leading 100 from said still to said reservoir, means preventing a back flow of refrigerant from said reservoir into said still, means for regulating the flow of refrigerant from said reservoir through said chamber, means controlled 105 by the reduction of the supply of refrigerant in said reservoir to a predetermined limit for starting a heating of said still, means for terminating such heating, and means for cooling the contents of said still 110 in its absorption period.

16. In combination a refrigerant reservoir, a still adapted to contain an absorbent, an expansion chamber leading from said reservoir to said still, a conduit leading 115 from said still to said reservoir, means preventing a back flow of refrigerant from said reservoir into said still, means for regulating the flow of refrigerant from said reservoir through said chamber, means con- 120

trolled by the reduction of the supply of refrigerant in said reservoir to a predetermined limit for starting a heating of said still, means for terminating such heating,

5 means for cooling the refrigerant driven off from said still by each such application of heat, and means for cooling the contents of said still in its absorption period.

17. In combination a refrigerant reservoir, a still adapted to contain an absorbent, an expansion chamber leading from said reservoir to said still, a conduit leading from said still to said reservoir, means preventing a back flow of refrigerant from said 10 reservoir into said still, valve means for controlling the flow of refrigerant through said chamber, a thermostat controlling said valve means, means controlled by the reduction of the supply of refrigerant in said 15 reservoir to a predetermined limit for suspending the operativeness of said thermostat and for starting a heating of said still, means for terminating such heating, means for making said thermostat operative after 20 such heating, and means for cooling the contents of said still in its absorption period.

18. In combination a refrigerant reservoir, a still adapted to contain an absorbent, 30 an expansion chamber leading from said reservoir to said still, a conduit leading from said still to said reservoir, means preventing a back flow of refrigerant from said reservoir into said still, valve means 35 for controlling the flow of refrigerant through said chamber, a thermostat controlling said valve means, means controlled by the reduction of the supply of refrigerant in said reservoir to a predetermined 40 limit for suspending the operativeness of said thermostat and for starting a heating of said still, means for terminating such heating, means for making said thermostat operative after such heating, means for 45 cooling the refrigerant driven off from said still by such application of heat, and means for cooling the contents of said still in its absorption period.

19. In combination a refrigerant reservoir, a still adapted to contain an absorbent, 50 an expansion chamber leading from said reservoir to said still, a conduit leading from said still to said reservoir, means preventing a back flow of refrigerant from 55 said reservoir into said still, valve means for controlling the flow of refrigerant through said chamber, a thermostat controlling said valve means, means controlled by the reduction of the supply of refrigerant in said reservoir to a predetermined 60 limit for suspending the operativeness of said thermostat and for starting a heating of said still, means for terminating such heating at a predetermined temperature 65 limit of the contents of said still, means

for restoring the operativeness of said thermostat at a lower temperature limit of such contents, and means for cooling the contents of said still in its absorption period.

20. In combination a refrigerant reservoir, 70 a still adapted to contain an absorbent, an expansion chamber leading from said reservoir to said still, a conduit leading from said still to said reservoir, means preventing a back flow of refrigerant from said reservoir into said still, valve means for controlling the flow of refrigerant through said chamber, a thermostat controlling said valve means, means controlled by the reduction of the supply of refrigerant in said reservoir to a predetermined limit for suspending the operativeness of said thermostat and for starting a heating of said still, means for terminating such heating at a predetermined 75 temperature limit of the contents of said still, means for restoring the operativeness of said thermostat at a lower temperature limit of such contents, means for cooling the refrigerant driven off from said still by such application of heat, and means for cooling the contents of said still in its absorption period.

21. In combination a refrigerant reservoir, a still adapted to contain an absorbent, an expansion chamber leading from said reservoir to said still, a conduit leading from said still to said reservoir, means preventing a back flow of refrigerant from said reservoir into said still, means for regulating the flow of refrigerant from said reservoir through said chamber, means controlled by the reduction of the supply of refrigerant in said reservoir to a predetermined limit for starting a heating of said still, means for normally terminating such heating, a safety device for operation in case the pressure in said still during such heating exceeds a predetermined limit to terminate such heating, and means for cooling the contents of said still in its absorption period.

22. In combination a refrigerant reservoir, a still adapted to contain an absorbent, an expansion chamber leading from said reservoir to said still, a conduit leading from said still to said reservoir, means preventing a back flow of refrigerant from said reservoir into said still, means for regulating the flow of refrigerant from said reservoir through said chamber, means controlled by the reduction of the supply of refrigerant in said reservoir to a predetermined limit for starting a heating of said still, means for normally terminating such heating, a safety device for operation in case the pressure in said still during such heating exceeds a predetermined limit to terminate such heating, means for cooling the refrigerant driven off from said still by such application of heat, and means for cooling the contents of said still in its absorption period.

23. In combination a refrigerant reservoir, a still adapted to contain an absorbent, an expansion chamber leading from said reservoir to said still, a conduit leading from said still to said reservoir, means preventing a back flow of refrigerant from said reservoir into said still, valve means for controlling the flow of refrigerant through said chamber, a thermostat controlling said valve means, means controlled by the reduction of the supply of refrigerant in said reservoir to a predetermined limit for suspending the operativeness of said thermostat and for starting a heating of said still, means for normally terminating such heating, a safety device for operation in case the pressure in said still during such heating exceeds a predetermined limit to terminate such heating, means for making said thermostat operative after such heating, and means for cooling the contents of said still in its absorption period.

24. In combination a refrigerant reservoir, a still adapted to contain an absorbent, an expansion chamber leading from said reservoir to said still, a conduit leading from said still to said reservoir, means preventing a back flow of refrigerant from said reservoir into said still, valve means for controlling the flow of refrigerant through said chamber, a thermostat controlling said valve means, means controlled by the reduction of the supply of refrigerant in said reservoir to a predetermined limit for suspending the operativeness of said thermostat and for starting a heating of said still, means for normally terminating such heating, a safety device for operation in case the pressure in said still during such heating exceeds a predetermined limit to terminate such heating, means for restoring the operativeness of said thermostat at a lower-temperature limit of such contents, means for cooling the refrigerant driven off from said still by such application of heat, and means for cooling the contents of said still in its absorption period.

25. In combination a refrigerant reservoir, a still adapted to contain an absorbent, an expansion chamber leading from said reservoir to said still, a conduit leading from said still to said reservoir, means preventing a back flow of refrigerant from said reservoir into said still, valve means for controlling the flow of refrigerant through said chamber, a thermostat controlling said valve means, means controlled by the reduction of the supply of refrigerant in said reservoir to a predetermined limit for suspending the operativeness of said thermostat and for starting a heating of said still, means for normally terminating such heating, a safety device for operation in case the pressure in said still during such heating exceeds a predetermined limit to terminate such heating, means for making said thermostat operative after such heating, means for cooling the refrigerant driven off from said still by such application of heat, and means for cooling the contents of said still in its absorption period.

26. In combination a refrigerant reservoir, a still adapted to contain an absorbent, an expansion chamber leading from said reservoir to said still, a conduit leading from said still to said reservoir, means preventing a back flow of refrigerant from said reservoir into said still, valve means for controlling the flow of refrigerant through said chamber, a thermostat controlling said valve means, means controlled by the reduction of the supply of refrigerant in said reservoir to a predetermined limit for suspending the operativeness of said thermostat and for starting a heating of said still, means for normally terminating such heating at a predetermined temperature limit of the contents of said still, a safety device for operation in case the pressure in said still during such heating exceeds a predetermined limit to terminate such heating, means for restoring the operativeness of said thermostat at a lower-temperature limit of such contents, means for cooling the refrigerant driven off from said still by such application of heat, and means for cooling the contents of said still in its absorption period.

27. In an absorption refrigerating apparatus, in combination, a still, a condenser, an evaporator, means for connecting said elements to form a circuit from the still through the condenser and evaporator back to the still, means operative at intervals to heat the still and subsequently to cool the still, temperature controlled means operative to regulate the flow of refrigerant through the evaporator in the intervals between such heatings, and means positioned at the outlet of the evaporator and operating to prevent a flow of refrigerant into the still during such heating.

28. In an absorption refrigerating apparatus, in combination, a still, a condenser, an evaporator, means for connecting said elements to form a circuit from the still through the condenser and evaporator back to the still, means responsive to a change in conditions in said circuit to heat the still and subsequently to cool the still, temperature controlled means operative to regulate the flow of refrigerant through the evaporator in the intervals between such heatings, and means positioned at the outlet of the evaporator and operating to prevent a flow of refrigerant into the still during such heating.

29. In an absorption refrigerating apparatus, in combination, a still, a condenser, an evaporator, means for connecting said elements to form a circuit from the still through the condenser and evaporator back to the still.

to the still, means for utilizing temperature and pressure conditions in said conduit to heat the still and subsequently to cool the still, temperature controlled means operative to regulate the flow of refrigerant through the evaporator in the intervals between such heatings, and means positioned

at the outlet of the evaporator and operating to prevent a flow of refrigerant into the still during such heating.

GEORGE P. CARROLL.
